UNITED STATES PATENT OFFICE.

EMIL TYDEN, OF EVANSTON, ILLINOIS.

SELF-LOCKING SEAL.

1,162,827.

Specification of Letters Patent.

Patented Dec. 7, 1915.

Application filed April 14, 1915. Serial No. 21,230.

To all whom it may concern:

Be it known that I, EMIL TYDEN, a citizen of the United States, and resident of Evanston, in the county of Cook and State 5 of Illinois, have invented new and useful Improvements in Self-Locking Seals, of which the following is a specification, reference being had to the accompanying drawings, forming a part thereof.

10 The purpose of this invention is to provide an improved form of self-locking seal of the general character of the seal shown in my Patent No. 739,037, September 15th, 1903, but designed to overcome a certain 15 ground of criticism to which that form of seal is liable.

In the drawings: Figure 1 is a side elevation of a seal embodying this invention at unlocked position of the strap. Fig. 2 is a 20 section at the line, 2—2, on Fig. 3, with the strap at locked position. Fig. 3 is a section at the line 3—3 on Fig. 1.

In the structure shown in the drawings 25 there is a shell composed of two members of sheet metal, A, A¹, clenched together, engaging a diaphragm, B, and a sheath, C¹, which is formed by folding upon itself the end portion of the strap, C, which constitutes the means by which the seal is engaged with the lock or device which it is 30 to protect. It will be understood that the strap is formed with a wide portion at one end adapted to be thus folded to form the sheath.

35 D, is a wire coil which is lodged within the shell, spread open and held open by the two sides of the sheath so as to permit the free end of the strap to be inserted through the sheath, but adapted to be sprung off 40 from the sheath and become engaged to the aperture, c, in said inserted end of the strap, thereby effecting the securement of the seal. Said inserted end of the strap is beveled as shown at C², to adapt it to trip the coil off 45 from the sheath and into engagement with said aperture of the strap.

The structure thus far described is the familiar one of the "Tyden seal", substantially as shown in said Patent No. 739,038, 50 and in my Patent No. 788,384, (the diaphragm mentioned not being shown in the first mentioned patent). In my said former patents the sheath is extended full width through the shell,—that is, it protrudes at

the farther end from the side of the shell 55 of the same width as at the side at which the strap end is inserted for sealing, and therefore the aperture in said farther wall of the shell is of the full width of said sheath. Inasmuch as the end of the strap 60 is beveled off for tripping the engaging coil for locking, and it is the beveled end which protrudes beyond the farther wall of this shell within the protruding portion of the sheath, there is afforded a small crevice at 65 the beveled end of the strap by reason of the width of the aperture and of the sheath being greater than the width of said strap at its beveled—and thereby reduced—end portion. Through this crevice it is said that 70 it is possible to insert a very small but strong steel wire hook, by means of which the spring coil device which engages the strap for sealing may be seized hold of and pulled out through the crevice, the wire coil 75 of course being straightened out and the spring device mutilated in the process, but with the effect of releasing the strap so that the seal may be disengaged from that which it secures. To obviate this difficulty, in the 80 structure shown in the drawings the end of the sheath which protrudes at the side of the shell opposite that at which the end of the strap is inserted for sealing is cut back in width to the width of the beveled end of 85 the strap at the point at which it occupies the aperture in the shell wall when at locked position, thus forming on the sheath a shoulder, c², which is stopped inside the wall of 90 the shell, the aperture through that wall of the shell being similarly reduced in extent so as only to permit the reduced end of 95 the sheath and the beveled end of the strap to pass through it. By this expedient access heretofore sometimes obtained for withdrawing the wire coil is prevented.

I claim:

In combination with the shell, the folded sheath extending therethrough; the strap continuous from one fold of the sheath at 100 one end thereof adapted to have its free end inserted through the sheath and through the shell; the wire coil in the shell for engaging the strap; the end of the strap being beveled off at one edge for tripping the wire 105 coil, and adapted to protrude its beveled end beyond the shell when at locked position, the shell having the aperture at the side at

which the strap thus protrudes limited in width substantially to the width necessary to accommodate the strap at said protruding beveled-end portion, the sheath being similarly reduced in width at that end, forming a shoulder which is stopped within the shell.

In testimony whereof, I have hereunto set

my hand at Chicago, Illinois, this 3d day of April, 1915.

EMIL TYDEN.
